W. F. Pagett.

Grain Binder.

Nº 15436

Patented Jul. 29, 1856.

Fig. 1.

UNITED STATES PATENT OFFICE.

WASHINGTON F. PAGETT, OF STONE BRIDGE, VIRGINIA.

IMPROVEMENT IN MACHINES FOR BINDING GRAIN, &c.

Specification forming part of Letters Patent No. 15,436, dated July 29, 1856.

To all whom it may concern:

Be it known that I, WASHINGTON F. PAGETT, of Stone Bridge, in the county of Clarke, in the State of Virginia, have invented a new and useful Improvement in Machines for Binding Wheat and other Grain in the Sheaf, and binding the same in the shocks; also for binding corn in the shock, and corn-fodder in the shock and bundles; and I do hereby declare that the following is a full and exact description thereof, reference being had to the accompanying drawings, and to the letters of reference marked thereon, in which—

Figure 1 is a side elevation, and Fig. 2 an end view thereof.

The nature of my invention consists in an improvement in machines for binding wheat and other grains in the sheaf or shocks, and corn-shocks and corn-fodder in the shock or bundles, with a metallic band, hereinafter described.

The machine is made as follows: A is a shaft. B is a rack. C is a driving-wheel. D is a band-conductor. E E are side pieces. F is the band-reel. G is the band. H is a fender. I is a spring. The side pieces E E are attached near the center of the shaft A, and have on their insides each two grooves—the upper just under the shaft A, the other some twelve inches below. These grooves, being opposite, form two rabbets, in the upper of which the rack B works; in the lower the conductor D works. The driving-wheel is about ten inches in diameter, and works between the side pieces E E. Its shaft projects on one side to receive a crank, and on the other acts as a spindle for the band-reel F. The shaft A is, when used for binding in the sheaf, about three feet long; the rear end, when of wood, about two inches wide by about one inch thick. The forward end may be somewhat reduced and rounded on the top, which, thus formed, serves as a way for the hook or ring of the band to slide upon, and has near its extremity an inclined hole for the attachment of the outward hook of the band G. The rack B has a line of cogs on its lower edge, and a loop or slide, J, on its forward end, which surrounds the way A and slides upon it, for the purpose of shoving off the hook or ring a. The reel F, which turns freely upon the spindle, has the bands wound upon it.

The operator will attach the outer hook b to

the forward end of the conductor D, which, having a line of cogs on its upper edge, is driven forward by the wheel C. Then unhook the other end from those on the reel F and hook it on the way A in front of the slide J, which is now withdrawn. The conductor is now run under the sheaf, and the hook removed from it and attached to the end of the way A, the sheaf being embraced by the band and a portion of the way A. The wheel C is now turned in a reversed direction, and the rack B slides the hook or ring off the end of the way A, when it grapples the other hook. The sheaf is thus compressed and securely bound, and the band disengaged from the machine.

Bands for the harvest may be wound on a drum attached to the water-car of the field, and wound from that onto the reel, as occasion requires; or the reel may have a series of detached rims, the empty one removed and a full one put on.

The machine may be used without the reel and conductor, in which case the way A will be run under the sheaf, having the ring of the band placed on the way in front of the slide; then attach the hook to the extremity of the way A, and move the ring off with the rack B and slide J. In using the machine thus it may be best to curve the shaft and rack so that the point of the way may be elevated. To curve the shaft A in the opposite direction will be advantageous in binding shocks.

If the cogs on the rack or conductor either hang in the straw, &c., the machine may be a little longer and the cogs on the rear end, or the cogs may be sunken. I propose also to work the rack and conductor by a strap, chain, or cord attached to the rear end of the rack or conductor, and to the driving-wheel, by turning which the rack or conductor will operate.

In working the curved rack, small friction-rollers may be used to make the operation easy—one in the loop or slide J, and one, perhaps, between the side pieces E E, and bearing against the rack. The spring I is used in connection with the band-reel F, and serves as a brake to steady the motion of the reel, and also to prevent the ends of the bands from falling down. The fender H is intended to raise the straw, &c., when the conductor is being withdrawn.

In binding the sheaf without the conductor, the way A, and that edge of the machine which had been uppermost, will be next to the ground, and the bands may be carried on the reel and drawn off by hand. The band G is about thirty inches long, having a hook at each end, or a ring at one end and a hook at the other.

The band may be flat, round, or of any other shape, and in strength about equal to a wire one-sixteenth of an inch in diameter. The length and strength will, of course, vary with the character of the substances to be bound.

The hooks b may be punched out of sheet-iron of proper thickness, or may be turned out of wire of sufficient strength, having a small turn at one end for the attachment of the band, and at the other a turn or bow large enough to fit on the way.

When a ring is substituted for one of the hooks b it must be large enough to pass over the way A, and may be made also of sheet metal.

In forming the wire hook one end may be flattened, and a hole punched through the flat to receive the end of the band, which is carried through, turned back, and a twist or two made to secure it.

The bands may have a loose or sliding hook, in addition to those described, for the purpose of locking together the capping-sheaves of the stack or rick.

The band a G b represents its position when the conductor is used to pass it under the sheaf, it then being put in the position shown by the band a G b' preparatory to its being compressed, the dotted band a G b'' representing it as in the act of being pushed forward to bind the grain.

Having thus described my invention and the manner of its operation, what I claim as my invention, and desire to secure by Letters Patent, is—

1. The way A, in combination with the slide J, or its equivalent, when operating in the manner and for the purposes described.

2. The band G, in combination with the way A and slide J, for the purposes described.

In testimony whereof I hereunto subscribe my name.

WASHINGTON F. PAGETT.
